UNITED STATES PATENT OFFICE.

STANLEY SEPTIMUS BOOTY, OF SUTTON, ENGLAND.

DEVICE ADAPTED TO CONTAIN POWDER.

1,334,218.

Specification of Letters Patent. Patented Mar. 16, 1920.

Application filed December 1, 1919. Serial No. 341,830.

To all whom it may concern:

Be it known that I, STANLEY SEPTIMUS Booty, a subject of the King of Great Britain and Ireland, and residing at Ennerdale, 5 Cedar Road, Sutton, in the county of Surrey, England, have invented certain new and useful Improvements in and Relating to Devices Adapted to Contain Powder, of which the following is a specification.

10 This invention relates to devices adapted to contain powder as, for instance, toilet powder, of the kind in which an openwork surface, which may be constituted by a piece of gauze held in a frame, is arranged above 15 the body of powder and in which a puff or the like device for use in applying the powder may be arranged in the space between the openwork surface and a closing means, the openwork surface being supported by 20 means adapted to permit the openwork surface to approach the base of the powder container when pressure is applied to the said surface and to cause the openwork surface to move away from the base of the container 25 when the pressure is removed and the space between the openwork surface and the closing means being preferably so proportioned that when the puff or other device employed in the distribution of the powder is inserted 30 in this space the puff will be held firmly between the closing means and the openwork surface by the resilient supporting means associated with the latter.

According to the invention the container 35 has flexible walls constituted, for instance, by the resilient supporting means when formed of rubber or the like, a sleeve of a flexible material enveloping the coils of a metallic spring, or by a bag secured to the 40 frame supporting the openwork surface.

In one construction in accordance with the invention, a spiral or other suitably formed spring may be interposed between the openwork surface and the base of the container, 45 the spring, if spiral, being of such diameter that at one end it bears on the periphery of the openwork surface which may be suitably reinforced where it contacts with the spring.

When the openwork surface is constituted 50 by a suitable textile fabric or gauze this will be arranged in a frame adapted to bear on one end of the spring.

In another construction in accordance with the invention, a resilient rubber member as, for instance, an annulus with tubular walls, may be arranged to bear on the

openwork surface near its periphery and on the base of the container.

In a third construction a plurality of resilient members are interposed between the openwork surface and the base of the container, and these resilient members may, for instance, be formed in metal being, for example, helical, spiral or volute springs or leaf springs, or they may be formed of rubber.

The walls of the container may be formed of rubber of sufficient thickness to act as a resilient support for the openwork surface.

As desired, the powder containers may be 70 constructed so as to be conveniently refilled or not, and in the former case a removable plug or lid may be provided in the base of the container or other means may be provided to facilitate replenishing the supply 75 of powder in the container.

In the construction in accordance with the invention the space adapted to accommodate the puff device may be constituted by a collar secured to the upper side of the powder container and a lid or closing device adapted to coöperate with the collar to secure the puff device in contact with the openwork surface.

It is preferred in the construction of devices in accordance with the invention to 85 make the openwork surface of less area than the area of the front surface of the puff with which the device is employed, as it is found that not only does this difference in 90 the area of the openwork surface and of the surface of the puff act in the direction of preventing undesired leakage of the powder through the openwork surface into the space between said surface and the closing device, 95 but in addition it possesses the advantage that only a portion of the puff becomes impregnated with the powder, the remaining portion which is not so impregnated facilitating the even distribution of the powder; a 100 point of particular importance when the device is employed with toilet powder.

Normally, the openwork surface will be so arranged that the center portion of the puff will be impregnated. Thus, when the 105 openwork surface is formed from a gauze, the frame to which the gauze is secured, if suitably proportioned, will act not only as a bearing surface for the resilient members, but also in the direction of localizing the 110 powder on the puff.

The invention is illustrated by way of ex-

ample in the accompanying drawings, in which:-

Figure 1 is a view in section of one construction of receptacle for powder in accordance with the invention;

Fig. 2 is a view thereof showing the lid removed and the puff pressed down.

In the drawings, 1 is the lid or closing means, 2 is the puff, 3 the perforated surface, 4 the frame thereof, 5 the spring which causes the openwork surface to move away from the base of the container, 6 a collar to which the flexible walled member 7 is secured by the ring 8, the flexible walled member being provided with a rigid base 9, the lid being adapted to hold the puff against the perforated surface.

Having now described my invention, what I claim as new and desire to secure by Letters Patent is:-

In a powder container, a rigid base, a rigid and apertured puff support, a flexible collapsible wall connected to the base and the support, a coiled spring arranged in proximity to the inner surface of the wall and bearing against the base and the support for normally holding the wall extended, and a flanged cover removably engaged with the support and coacting with the support to form a powder puff receiving chamber.

In testimony whereof I have signed my name to this specification.

STANLEY SEPTIMUS BOOTY.
